UNITED STATES PATENT OFFICE

PIERRE P. GILLES, DECEASED, LATE OF SPRINGFIELD, MASSACHUSETTS, BY FLORENCE
MAY GILLES, ADMINISTRATRIX, OF CORTLAND, NEW YORK

OIL BURNER

Application filed July 31, 1928. Serial No. 296,617.

This invention relates to improvements in oil burners of the type in which the oil and air are mixed together by means of a rotatable turbine member through which the oil and air 5 are forced.

Broadly, the invention comprises a base member which is formed with a groove or channel around the outer upper edge for the purpose of collecting and returning any surface oil. A vertically arranged shaft is employed to the upper end of which is secured a conical shaped turbine member through which the oil and air under pressure escape and are intermixed. This member is located 10 within the fire box of a furnace, either steam or hot water.

The invention further comprises means for thoroughly lubricating the rotating parts. The invention further comprises means for 20 rotating the vertical shaft from a horizontally arranged shaft, the connecting driving means comprising two beveled shaped cones which are covered with leather or other material for producing a noiseless drive. The 25 invention includes means for distributing the air through a member having inclined shaped partitions which are located adjacent the oil outlets.

Referring to the drawings:

30 Fig. 1 is a plan view of the burner removed from the furnace compartment showing the vertically arranged shaft, the cone shaped bowl, the pilot jet and the driving connections between the shaft and operating member.

Fig. 2 is an enlarged elevational view partly in section, showing the pilot jet and the rotatable cone-shaped member in side elevation and located within the furnace.

40 Fig. 3 is an enlarged vertical sectional view on the line 3—3 of Fig. 1 showing the detail construction of the rotatable turbine member, the driving means for the member and the oiling system.

45 Fig. 4 is a horizontal sectional view on the line 4—4 of Fig. 3 of the turbine member on a larger scale, showing the construction of the inclined partitions of the rotatable turbine member.

50 Fig. 5 is a detail, sectional view on the line

5—5 of Fig. 4 and Fig. 6 is a modification of the burner mixer.

Referring to the drawings in detail:

1 designates the base piece of the burner which is supported by means of the legs 2. 55 1' is a cylindrical upright or casting that is secured to the base 1 by means of the screws 1''. This base piece is formed around its outer edge with the oil collecting groove 4 which terminates at the oil strainer 5. 6 60 6 designates the pipe which conducts the oil back to the oil supply tank 7 from the basin 69. Mounted on the base piece is the electric motor 8. Connected to the motor 8 is a shaft 9, the inner end of which is supported in the 65 bearing 10. 11 represents the ball bearing construction for supporting the shaft 9. 12 is a slidable plate located in the bearing 10. This plate is formed with the openings 13. 14 is a plate which is threaded into the end of 70 the bearing 10, and 15 is a spring for normally forcing the plate 12 against the bearing 16. The opening 13 registers with the opening 17 of the ball bearing. On the inner end 75 of the shaft 9 is secured the cone pulley 18 by means of the woodruff key 19. This pulley is formed with a leather face 20. This face piece is secured to the cone pulley 18 with the screws 21. 22 is a vertically arranged shaft 80 that is supported at the bottom by the ball bearings 23 and at the top with the ball bearing 24. 25 is a sleeve which encloses the shaft 22. 26 is a cone shaped pulley secured to the shaft 22 by means of the key 27. 28 is a pipe 85 which extends from the recess 29 to the upper recess 30. The lower end of the shaft 22 is attached to the plate 31. 32 is another plate that is attached to the shaft 22. The plates 31 and 32 serve as a pump to force the oil upward through the pipe 28 into the space 30, 90 then downward through ball races 33, then through the pipe 34 into the space 35 where it lubricates the balls 11 in races 16 and 36, then passing through the space 37, ball bearing 23 to the pump again. The shaft 22 is 95 formed with an enlarged portion 38 which is located in a sleeve 39, that is threaded into the cap piece 40. Located outside of the sleeve 39 is a second sleeve 41. 42 is a cone shaped member that is secured to the shaft 22 100

by the key 43. Formed integrally with the part 42 is an upwardly extending bowl shaped turbine member 44. The part 42 is spaced from the part 44 by means of the webs 5 45. These webs are inclined, as shown in Fig. 5 and have openings 46 therebetween. Located adjacent the inner surface of the part 42 are openings 47. Threaded onto the upper end of the shaft 22 is a saucer shaped member 48, the outer edge portion 49 of which is located above the upper edge of the part 50 which provides an annular oil escape space 51. 52 is an internally threaded cap that secures the saucer shaped member 48 on 10 15 to the upper end of the shaft 22. Formed in the cap piece 40 is a passageway 53 which receives the discharge end of the oil supply pipe 54. The oil from the passageway 53 flows upward through the nozzle piece 55 20 which is formed with a very small opening. Surrounding the cone-shaped member 42 is a cap 56 which is secured to the cap piece 40 by means of the bolts 57 only one of which is shown and a spring 58 to provide yielding 25 or an elastic side bearing or support for the cone-shaped member 42.

Referring to Fig. 1, 59 is a pipe that is connected with the gas main of the city for supplying the pilot jet 60. 61 is a cap located 30 over the pilot jet 60 which is formed with an opening 62. The turbine member 44 is located within the furnace of the heater which may be either hot water or steam. The refractory material of the furnace is indicated 35 at 63. It will be noticed that the oil groove 4' is located immediately below the passageway 64, to receive and carry off any surplus oil or to carry off the oil should the burner go out. The pipe 54, it will be understood, 40 extends to the pump 65, and connected with this pump is a pipe 66 that leads back to the fuel tank 7. 66' is a valve for controlling the oil from the basin 69. 67 is a belt extending from the pulley on the shaft 9 and to a pulley 45 68 for driving the pump 65 from the motor 8, and forcing the fuel oil through the pipe 54 to the turbine member. A tiltable drip basin 69 is provided which operates a switch 69' to open a circuit to the motor. A pipe 50 70 conducts oil from the basin 4', in case the burner goes out, to the drip basin and a pipe 71 connects the pipe 54 leading to the burner to the drip basin which basin is connected to the tank 7 by a pipe 7'. This is so in case 55 pipe 54 is closed, oil will be delivered back to tank 7.

The weight of the collected oil in the drip basin 69 will automatically cut off the electric current to the motor 8, thereby preventing further suction of the oil from the tank. The operation of the drip basin 69 will open an electric switch 69' in the motor circuit.

The operation is as follows: It is assumed that oil is flowing through the pipe 54 into 65 passageway 53, then through the nozzle piece

55 where it is forced upward into the inside of the rotatable part 42, then by means of centrifugal force the oil escapes through the openings 47 where it meets the air which is drawn upward through the openings 46 of the rotatable turbine member 44. The air and the oil are thoroughly intermixed at the point 51 where it finally escapes and burns at the upper end at the turbine bowl member 44. The flame is therefore spread outward in a mushroom manner within the furnace. 72 is a valve which automatically controls the flow of gas to the pilot light 60. This valve is operated by the pressure of the pump and does not form any part of the invention. 70 75 80 85 90

From this description it will be seen that there has been provided an oil burner which, by means of a rotatable turbine member thoroughly mixes or atomizes the oil and air in the furnace compartment. 44 extends above the spreader 48 for thoroughly mixing the oil and air as the same is rapidly rotated. 95

Referring to Fig. 6, 73 designates a flame spreader plate which is located, as shown, a short distance above the upper peripheral edge 74 of the turbine fuel mixing member 44. This plate is secured to the upper end of the shaft 22 by means of the short stud 75 which, as shown, is internally threaded at 76 for connection with the threaded upper end of the shaft 22. Its upper end is formed with a threaded end 77 to receive the securing nut 78. The annular space 79 permits the flame to be spread out in a horizontal direction as the mixing member 44 is rapidly rotated. 100

What is claimed is:

1. In oil burning apparatus, the combination of an oil container, driving mechanism below the same, the container having its bottom formed with an elevated portion provided with an aperture, an atomizing element having an upwardly diverging receiving end dipping into the container, and driving connections between said element and the driving mechanism passing through said aperture. 105 110 115

2. In oil burning apparatus, the combination of a reservoir having its bottom formed with a re-entrant portion that is provided with an opening at its top, an atomizing element having a hollow upwardly diverging receiving end dipping into the reservoir about said re-entrant portion, and means extending upwardly through said re-entrant portion for rotating the atomizing element. 120 125

3. In oil burning apparatus, the combination of an open-top reservoir, an atomizing cup whose peripheral wall merges into an integral depending and upwardly diverging sleeve-like extension, a perforated bottom set within the cup at its junction with said extension, means connected to said bottom for rotatably supporting the cup with 130

said extension in the reservoir, and means for rotating the atomizing cup.

4. In oil burning apparatus, the combination of an open-top reservoir having its bottom formed with a re-entrant portion that is also open at the top, a driving shaft disposed axially of said re-entrant portion, and an atomizing element having a hollow upwardly diverging receiving end extending into the reservoir about said re-entrant portion and arranged to have separable driving connection with said driving shaft.

5. An oil burner apparatus comprising in combination, a support and a shaft rotatable therein, a lower tubular member having an interior part spaced downwardly from its upper end which is secured to said shaft and which is provided with openings therethrough, an upper tubular member having its lower end extending below the outside and upper end of the said upper member which is spaced therefrom, parts connecting the lower end of the upper member and the upper end of the upper member which are in spaced relation to provide openings therebetween, a member within the upper end of the lower member which extends upwardly and outwardly to have a part in spaced relation with respect to the upper end of the lower member to provide an oil escape passageway.

6. An oil burner apparatus comprising in combination, a support with a shaft rotatable therein, a lower tubular member having an interior part below its upper end which is secured to said shaft and is provided with openings therethrough, a rim extending upwardly from said support around said lower member to provide a chamber, a cap embracing said lower member yieldingly mounted on said rim, an upper tubular member extending upwardly from and outside the lower member having its lower portion below the upper end of the inner member and secured thereto by parts disposed in an angular relation forming angularly disposed blades between the upper and lower members, a part within the lower member having an inclined peripheral face which extends upwardly therein in a spaced relation from the upper end of the inner member to provide an oil escape passageway therebetween.

7. An oil burner apparatus comprising in combination, a support with a shaft rotatable therein, a lower tubular member having an interior part below its upper end which is secured to said shaft and is provided with openings therethrough, a rim extending upwardly from said support around said lower member to provide a chamber, a cap embracing said lower member yieldingly mounted on said rim, an upper tubular member extending upwardly from and outside the lower member having its lower portion below the upper end of the inner member and secured thereto by parts disposed in an angular relation form-

ing angularly disposed blades between the upper and lower members, a part within the lower member having an inclined peripheral face which extends upwardly therein in a spaced relation from the upper end of the inner member to provide an oil escape passageway therebetween and a flame spreader supported on the upper end of the shaft so that it will overlie the upper end of the upper member in a spaced relation therefrom to form a space therebetween and said upper edge.

8. An oil burner apparatus comprising in combination, a support having a shaft journaled on a vertical axis therein, a lower cone member having its walls diverging upwardly which is secured to said shaft by an inner part disposed within and below the upper open end thereof, the said part being provided with openings therethrough, an upper cone shaped member having its lower end disposed below and outside the upper end of the lower member with its side walls extending in a diverging relation upwardly therefrom, the upper end of the lower and the lower end of the upper cone members being staggered and connected in a spaced relation by angularly disposed parts arranged in spaced relation to form openings therebetween, a spreader member having an upwardly diverging peripheral surface mounted on said inner part of the lower cone member so that the peripheral surface thereof is spaced from and extends over and above the upper edge of the lower cone member to form an oil escape passageway therebetween.
